UNITED STATES PATENT OFFICE

159,694

PLAYING CARD

Ulysses Simpson Surratt, Kansas City, Mo.

Application April 14, 1948, Serial No. 145,723

Term of patent 3½ years

(Cl. D34—13)

To all whom it may concern:

Be it known that I, Ulysses Simpson Surratt, a citizen of the United States, residing at Kansas City, in the county of Jackson and State of Missouri, have invented a new, original, and ornamental Design for a Playing Card, of which the following is a specification, reference being had to the accompanying drawing, forming a part thereof.

Fig. 2 is an edge view of the playing card.

The back of the card is of conventional appearance.

I claim:

The ornamental design for a playing card, as shown and described.

ULYSSES SIMPSON SURRATT.
